UNITED STATES PATENT OFFICE.

JOHN J. SPEER AND RUDOLPH W. ZEDLITZ, OF WATERBURY, CONNECTICUT.

LOCOMOTIVE.

SPECIFICATION forming part of Letters Patent No. 591,020, dated October 5, 1897.

Application filed February 13, 1896. Serial No. 579,140. (No model.)

To all whom it may concern:

Be it known that we, JOHN J. SPEER and RUDOLPH W. ZEDLITZ, citizens of the United States, and residents of Waterbury, in the county of New Haven and State of Connecticut, have invented certain new and useful Improvements in Locomotives, of which the following is a specification.

Our invention relates to new and useful improvements in feed-water distributers and combined blow-off cocks and fire-extinguishers for locomotive or other engine boilers.

It is the object of our invention to provide for a locomotive-boiler a desirable and novel feed-water distributer which will be adapted for use in old or new boilers of any ordinary construction.

It is also an important object of our invention to provide a surface blower whereby the principal settlements of the water are conveniently discharged and the boiler thus cleaned, and, further, to use said surface blower in connection with a cock of special construction and having a pair of check-valves. By means of the above specially-constructed cock and valves we are enabled to get at (for repairs or other emergencies) either one of said valves without disturbing the other and without disabling the engine by having to draw the fire.

Referring to the accompanying drawings, which form a part of this specification, the same reference-characters denote like or corresponding parts upon the several figures, and of which—

Figure 1 is a central vertical section of a locomotive provided with our improvements. Fig. 2 is an enlarged detail cross-section on line $z z$ of Fig. 1. Fig. 3 is a similarly-enlarged longitudinal sectional view of our novel mechanism, which view agrees with Fig. 1. Fig. 4 is a plan view of Fig. 3, the surface blow-off pipes being broken. Fig. 5 is an enlarged detail cross-section of the feed-water distributer. Figs. 6 and 7 are a side elevation and plan view, respectively, of the combined blow-off cock and check-valves. Figs. 9, 10, and 11 are vertical longitudinal sectional views on line $z z$ of Fig. 7, showing the valve of the cock in three different positions, the purposes of which will be later described.

Referring to the reference-characters upon

the drawings, A indicates the boiler of a locomotive, B the fire-box, and C the flues running lengthwise of the boilers.

D indicates our novel feed-water distributer, E the surface blow-off, and F the cock employed in connection therewith.

Our novel feed-water distributer is preferably located in the bottom of a boiler immediately below the series of flues and over the water-supply pipe. It is made of about one-quarter-inch sheet or boiler plate in two sections, so as to readily admit of its introduction into the boiler prior to being assembled. These two sections, which I will designate as 1 and 2, are secured together by means of rivets or bolts 3 and are fastened to the boiler by means of brackets 4. Said sections 1 and 2 are placed at an angle of about one hundred and twenty degrees to each other and are broader in the center over the supply-pipe than at their outer ends, thus insuring said water-supply traveling lengthwise under said distributer until near the ends, where it gradually escapes on each side by reason of the increased space between said distributers and the bottom of the boiler. The water is in this manner distributed more evenly throughout the numerous flues and thereby increases its temperature before the same comes into contact with said heated flues.

By the above means of distribution water of a low temperature is prevented from coming into direct contact with the flues, thereby reducing contraction and thus lengthening the life of said flues. As before stated, the distributer is made angular in cross-section—that is, higher in the center than on the edges. Upon the under side of the ridge of said distributer we secure small hangers 5, which support the main blow-off pipe E, running lengthwise therewith and provided with the two upwardly-curved branches 5 and 6, having enlarged funnel-shaped mouths 7, which finish flush with the surface of the water in the boiler. The lower extremity of this blow-off pipe E is turned downward, as at 8, in such a manner that the end thereof terminates immediately above the discharge-cock, but is not connected therewith.

In view of the foregoing it will be apparent that when the cock F is opened, as in Fig. 11, the contents of the boiler has a direct and

free outlet through said cock, which would necessarily create a suction through pipe E and its branches 5 and 6. Said suction acts to draw in the impure surface water, and particularly the water from over the crown-seat, where the majority of settlement takes place.

The combined blow-off cocks F and check-valves will be best understood with reference to Sheet 3 of the drawings, and consists of a suitable body 9, provided with a four-way valve 10, having the direct passage a and the intermediate passage b. This valve 10 is provided with cranks 11 and 12, having suitable link connections 13 with operating-levers (not shown) in the cab and whereby said valve is operated to perform its several functions. Upon each side of the body and in line with the center of the valve are provided threaded nipples 14 and 15, to which are attached, by means of couplings 16, the check-valves 17 and 18, respectively. Thus it will be apparent that said valves are independently connected and can be detached separately without disturbing the other or effecting the operating of the engine.

By means of the convenient location of the check-valves with respect to the cock and the mechanism for shifting the same it is possible to use one or both of them, as desired. They can also be used as a fire-extinguisher independent of any action or assistance on the part of the boilers. In this case it is obvious that the hose-pipe to play upon the fire would be connected to the under side of the cock, as shown in dotted lines in Fig. 3, and, further, that it would be fed by the injectors through the check-valves and passages a and b of the cock when in the position shown in Fig. 10. During the time the apparatus is being used as a fire-extinguisher it is obvious that the boiler has got to be fed with water and that the check-valves and their injectors cannot be used for that purpose, inasmuch as they constitute a part of the extinguisher. Therefore we supply a third supply-pipe G and an intermediate passage

c, through which the water is fed to the boiler during the time the cock is acting as a fire-extinguisher.

Having thus described our invention, what we claim, and desire to secure by Letters Patent, is—

1. The combination with the boiler of a locomotive having a water-supply inlet, of a water-distributer placed over said inlet and consisting of an angular sheet-metal covering the length of which is greater than its width, and said width being greater at its center, means for securing said distributer to the boiler.

2. The combination with a boiler provided with a water-supply cock, of an inverted-trough-like deflector arranged over said supply, a blowpipe adjacent to said cock, connections of said pipe with the surface water in the boilers, whereby said impure surface water is discharged through said blowpipe and the cock above mentioned.

3. The combination with a boiler provided with a blow-off cock, of a blow-off pipe connected with the surface water of said boiler and terminating adjacent to, but not connected with said cock, means for opening said cock and creating a suction through said blow-off pipe, substantially as described.

4. The combination with a boiler, of a blow-off pipe therein, the mouth of which is substantially in line with the surface water of the boiler, a cock adjacent to the mouth of said pipe, check-valves connected with said cock and adapted to feed the boiler therethrough, means for manipulating said cock to feed the boiler and also for blowing off the same, substantially as described.

Signed at Bridgeport, in the county of Fairfield and State of Connecticut, this 1st day of January, A. D. 1896.

JOHN J. SPEER.
RUDOLPH W. ZEDLITZ.
